UNITED STATES PATENT OFFICE.

JAMES T. HOUSE, OF TALALA, INDIAN TERRITORY.

STIRRUP.

SPECIFICATION forming part of Letters Patent No. 608,605, dated August 9, 1898.

Application filed August 3, 1897. Serial No. 646,909. (No model.)

To all whom it may concern.

Be it known that I, JAMES T. HOUSE, of Talala, Indian Territory, have invented certain new and useful Improvements in Stirrups, of 5 which the following is a full, clear, and exact description, reference being had to the accompanying drawings, forming a part thereof.

My invention relates to stirrups, and more particularly is designed for use in connection 10 with wild, unbroken, or kicking horses.

The object of the invention is to produce a swiveled stirrup whereby the rider when standing at the head of the animal and facing to the rear may place his near foot securely in the stirrup and then as he vaults into the saddle cause the stirrup to swing half-way around and assume its proper position for riding.

A further object of the invention is to produce a swiveled stirrup which is positive and reliable in action and simple, strong, durable, and cheap of construction.

With these objects in view the invention consists in certain novel and peculiar features of construction and combinations of parts, as will be hereinafter described and claimed.

In order that the invention may be fully understood, I will proceed to describe it with 30 reference to the accompanying drawings, in which—

Figure 1 represents in perspective a stirrup embodying my invention. Fig. 2 represents, on a smaller scale, a horizontal section 35 of the same and also shows the lower member of the stirrup in one position it assumes when rotating from the position it occupies in Fig. 1—viz., the position for mounting—to the position it occupies in Figs. 3 and 4—viz., 40 the position for riding. Fig. 3 represents a vertical section of the upper portion of the stirrup. Fig. 4 represents a full-sized plan view of a part of the upper portion of the stirrup. Fig. 5 represents a perspective view 45 of the pivot or swivel pin.

My improved stirrup comprises, essentially, a lower and an upper portion or member swiveled together.

The lower portion or member comprises a 50 stirrup or foot-guard proper, 1, and a top piece 2, riveted to and connecting the upper ends of the stirrup proper or foot-guard, and

said top piece is provided centrally with a rectangular opening 4.

The upper member of the stirrup comprises 55 the U-shaped bracket 5, provided with a circular centrally-located opening 6, preferably equal to or exceeding the size of the opening 4, and a circular recess 7, concentrically surrounding the opening 6, so as to form a horizontal shoulder 8. A pin 9, riveted or swaged at its ends, connects the upper ends of the arms of the U-shaped bracket 5, and journaled upon said pin is a roller 10, adapted for engagement with the stirrup-strap. (Not shown.) In 60 practice the bracket 5 rests upon the cross-piece 2 with the opening 6 in alinement with the opening 4, and such position is maintained by means of a swivel or pivot pin. This pin 65 comprises the rectangular stem 11, a circular neck 12, and a circular head 13, of greater diameter than the neck, said head, however, being cutaway, so as to form the abrupt shoulders 14 and 15 almost diametrically opposite each other, but not quite. This pin is arranged 70 so that the rectangular stem 11 engages the rectangular opening 4, the neck 12 engages the opening 6, and the head 13 occupies the recess 7 and rests upon the shoulder 8. The lower end of the stem is then upset 75 or swaged, so that the lower and upper members of the stirrup shall be permanently united.

By this construction and arrangement it will be obvious that the stirrup may be rotated 85 completely around, and in order to prevent any more than a half-revolution being made the pin 16 projects from the bracket 5 into the recess 7, so as to be struck alternately and at opposite sides by the shoulders 14 and 15 of the swivel or pivot pin, the arrangement 90 being such that when the stirrup is in the position for riding the shoulder 14 engages the pin, as illustrated in Fig. 4, and when in position for mounting a dangerous animal the shoulder 15 engages the pin, as shown in Fig. 1.

As well known, stockmen are compelled to ride all kinds of horses, most of them at least half wild. It is dangerous to attempt to mount these animals from the side or from the rear, 100 owing to their kicking tendencies, and as a consequence a cautious rider almost invariably mounts from the horse's head, where he can keep a firm grip upon him until the in-

stant he leaps to the saddle. This, of course, is very difficult with the ordinary stirrups, as they do not readily admit of the reversal of the stirrup and also are liable to fail to swing 5 back to their original position properly as the rider attempts to mount, and consequently it is dangerous to attempt to mount a vicious or unbroken animal from the only really safe place with such stirrups.

- 10 If an animal of the type described be provided with a stirrup embodying my invention, the rider first grasps it and rotates it half around until the shoulder 15 strikes against the pin 16, as shown in Fig. 1. He then, without moving from the horse's head, places his left foot (according to Fig. 1) in the stirrup and vaults to his seat in the saddle. As he swings to position the stirrup rotates in the direction indicated by the arrow, Fig. 2, until
- 15 the shoulder 14 strikes the pin 16, as illustrated in Fig. 4, the stirrup having completed just a half-revolution. When dismounting, the stirrup will swing in the opposite direction enough to accommodate the position of
- 20 the rider's foot, so that he may easily withdraw it, and in case he falls from the saddle there will be little danger of his being dragged along the ground, owing to the fact that the twisting movement of his foot due to his fall
- 25 will cause a corresponding movement of the stirrup and will be easily disengaged therefrom for that reason.

From the above description it will be apparent that I have produced a stirrup which embodies the features of advantage enumerated in the statement of invention, and it is to be understood, of course, that changes in 35 the form, proportion, or arrangement of parts

may be resorted to which do not involve a departure from the principle of construction involved. The stirrup preferably will be made of wrought metal, but may be made of any other suitable material or combinations of material.

Having thus described the invention, what I claim as new, and desire to secure by Letters Patent, is—

1. A stirrup, comprising the lower or foot-receiving member, provided with a rigid stop-pin, and an upper member to which the stirrup-strap is attached, swiveled or pivoted to the lower member, and provided with a semi-circular slot or recess engaging said pin, and extending concentrically around the swivel or pivotal point, to permit the lower member 55 to rotate freely in a horizontal plane until said stop-pin reaches one end or the other of said slot, substantially as described.

2. A stirrup, comprising a lower member, to receive the rider's foot, a pin carried thereby and provided with a cylindrical neck and a circular head having shoulders 14 15, an upper member provided with a circular hole embracing the neck of the pin, and a recess embracing the head of said pin, and a rigid 65 pin 16, projecting into said recess and limiting the rotatable movement of the lower member by contact with shoulder 14 or 15 of the head of the pivot or swivel pin; substantially as described.

In testimony whereof I affix my signature in the presence of two witnesses.

JAMES T. HOUSE.
